UNITED STATES PATENT OFFICE.

RUFUS B. BAKER AND GEORGE H. STRAW, OF CLAREMONT, N. H.

MACHINE FOR UNITING KNIT FABRICS.

SPECIFICATION forming part of Letters Patent No. 317,702, dated May 12, 1885.

Application filed February 29, 1884. (Model.)

To all whom it may concern:

Be it known that we, RUFUS B. BAKER and GEORGE H. STRAW, both of Claremont, in the county of Sullivan and State of New Hampshire, have invented certain new and useful Improvements in Machines for Uniting Knit Fabrics by Sewing, (which machines are technically known as "circular-looping machines,") of which the following, in connection with the accompanying drawings, is such a clear and exact description as will enable those skilled in the art to which our invention relates to make and use the same.

The object of our invention is to provide a simple mechanism by which the surplus material of cut knit fabrics, outside of the seam or line of sewing, may be neatly trimmed off mechanically during the operation, uniting the fabrics by sewing, but just before the fabrics are presented to the stitch-forming mechanism of the machine. By the use of our invention the trimming and sewing operations are simultaneously effected, thereby obviating the necessity of trimming the work with hand-shears, as has usually been the practice heretofore.

In the drawings, in which similar letters indicate similar parts in the different views, Figure 1 is a perspective view showing the details of our invention. Fig. 2 is a detail plan view of the needle-guard; Fig. 3, an elevation of the knife-carrying arm. Fig. 4 is a sectional elevation of the needle-guard, showing the waste-pan, the stationary knife or blade, and the means for connecting the latter to the needle-guard. Fig. 5 is a plan view of the waste-pan, waste-guard, and the arm by which these parts are attached to the needle-guard. Fig. 6 is a plan view of a circular-looping machine, showing our invention in operation relative to the stitch-forming mechanism thereof. Fig. 7 is an elevation of the same, and Fig. 8 is a detail sectional view.

I is a supporting plate or bracket having standards i^3 and i^3 , in which is journaled the driving-shaft I^2 . An arm, i^4 , attached to the standard i^3 , sustains the bar K, supporting a disk, K' , on which revolves the rotary needle or pin plate L^2 , provided with impaling needles or pins l . This pin-plate receives an intermittent rotary movement in the direction indicated by the arrows in Figs. 6 and 7 from

the eccentric m on the shaft I^2 through pawl-arm M and ratchet-wheel N on a small shaft, n , on the under side of the disk K' , said shaft carrying a pinion, n^2 , meshing with a circular rack or contrate gear, l^2 , on the pin-plate L^2 .

O is the looper-arm, carrying a looper, o, and operated by a cam, o^2 , on the shaft I^2 ; and p is the needle carried by an arm or bar, P, operated by a grooved eccentric, p^2 , on the shaft I^2 . The needle arm P is provided with a sleeve, H, by which it is pivoted on a stud, i^5 , extending horizontally from the arm i^4 , said sleeve being retained on said stud by a collar, i^6 , secured by a set-screw, i^7 .

The parts thus far described are, or may be, of ordinary or well-known construction, and, not being new, their operation is understood by those familiar with this class of machines, and need not therefore be more fully indicated, our invention relating to the mechanism, which we will now describe.

A indicates a plate, which we term a "needle-guard," said plate being attached to the disk L^2 , and having an opening, a^2 , in which the looper o can work, an aperture, i, through which the needle p can pass, and a notch, h, in its edge.

A' is an arm, preferably of spring metal, attached to the needle-guard A by a screw, G, which is, or may be, one of the screws by which the said needle-guard is secured to the disk L^2 . The arm A' carries at its outer end a block or knife-holder, h' , fitting in the notch h of the needle-guard, said block, as herein shown, being attached to said arm by a screw, b. The block or knife-holder h' has a dovetailed or under-cut groove, in which is held the stationary knife or ledger blade k.

C is a knife-carrying arm, rigidly attached by means of a split-eye and a set screw, c, to the needle-bar sleeve H. To the lower end of the vibrating arm C is secured by a screw, a, a knife-holder, B, carrying the movable knife or blade d, arranged to come in contact with and just above the stationary knife or blade k, and thus these knives can cut like shear-blades. The stationary knife can be adjusted to bring it into proper position relative to the movable knife by means of an adjusting-screw, a^3 , passing through the arm A' and abutting against the needle-guard A. (See Fig. 8.)

D is a waste-guard attached by the screw

b to the arm *A'*, the free or forward end of said waste guard being bent downward, so as to be nearly in contact with the pins of the pin-plate, and the outer edge thereof being inclined, as shown in Figs. 5 and 6.

5 *F* is a waste-pan hinged at *e* to the waste-guard *D*, the inner edge of the outer portion of said waste-pan being inclined, as shown in Figs. 5 and 6, in a direction opposite to that 10 of the outer edge of the waste-guard, the adjacent edges of these two parts thus converging rearwardly toward each other.

15 The toe *b'* of the movable knife-holder *B* is arranged to strike against the under side of the hinged waste-pan and lift the same slightly at each stroke; and *L* is a spring pressing against the rear side of said waste-pan, and thus serving to return the latter after it has 20 been lifted by the toe *b'*.

20 The operation of our invention is as follows: The fabrics to be trimmed and sewed being impaled on the pins *l* of the pin-plate *L'*, and the machine being set in motion, the fabrics will approach the trimming and stitch-forming mechanisms. The edges of the fabrics, projecting above the pins *l*, are liable to curl more or less; but as said edges approach the cutting blades or knives the downwardly-turned end and inclined inner edge of the waste-guard 25 will deflect the curled edges outwardly, and thus straighten them up, if they be curled inwardly, while the inclined inner edge of the spring-pressed waste-pan will tend to deflect them in the opposite direction, thus bringing 30 the edges to be trimmed into a vertical position, so that they will be passed between the knives or blades *d* and *h*, and as the former blade, vibrating with the needle-bar and needle, comes in contact with the latter blade, 35 the projecting edges of fabrics will be closely sheared off, after which the trimmed fabrics will be united by the stitch-forming mechanism in the usual manner. The surplus or waste material trimmed off will be received 40 by the waste-pan *F*, and the vibrating movements of the latter will assist in deflecting the loosened or trimmed-off material away from 45

the pin-plate, thus preventing it from getting in the way of the stitch-forming mechanism.

Having thus described our invention, what we claim, and desire to secure by Letters Patent, is—

1. The combination, with the pin-plate of a looping-machine, of a stationary knife or blade and a vibrating knife or blade moving coincidently with the needle and having a shear contact with the stationary blade, substantially as set forth. 55

2. The combination, with the pin-plate, the stationary knife or blade, and the movable knife or blade, of the waste-guard and the waste-pan, substantially as set forth. 60

3. The combination, with the pin-plate, the stationary knife or blade, and the movable knife or blade, of a waste-guard and a waste-pan, said waste-guard and waste-pan having adjacent inclined edges converging rearwardly toward each other, substantially as set forth. 65

4. The combination, with the pin-plate, of the needle-guard *A*, the arm *A'*, attached thereto and having the knife-holding block *h'*, carrying the stationary knife *h*, the vibrating arm *C*, having the knife-holder *B*, carrying the movable knife *d*, the waste-guard *D*, and the waste-pan *F*, substantially as set forth. 70

5. The combination, with the pin-plate, the needle-guard, the arm attached thereto, the waste-guard, the hinged waste-pan, its returning-spring, and the stationary knife, of the vibrating arm *C*, the knife-holder *B*, having 80 the toe *b'*, and the movable knife *d*, carried by said holder, substantially as set forth.

6. The combination, with the pin-plate and the stationary knife, of the needle-bar sleeve *H* and its operating mechanism, the arm *C*, 85 secured to said sleeve, the knife-holder *B*, carried by said arm, and the movable knife *d*, attached to said knife-holder, substantially as set forth.
